(57) CLAIM

The ornamental design for a lawn lamp, as shown and described.

DESCRIPTION

FIG. 1 is a left, front, top perspective view of a lawn lamp showing my new design;

FIG. 2 is a right, rear, bottom perspective view thereof;

FIG. 3 is a left side elevational view thereof;

FIG. 4 is a right side elevational view thereof;

FIG. 5 is a rear plan view thereof;

FIG. 6 is a front plan view thereof;

FIG. 7 is a top elevational view thereof;

FIG. 8 is a bottom elevational view thereof; and,

FIG. 9 is an enlarged view of circled portion in FIG. 1. The short dash-short dash broken lines in the drawings depict portions of the lawn lamp that form no part of the claimed design.

The short dash-long dash broken lines in the drawings depict the boundaries of the enlarged views and form no part of the claimed design.
